COMBINED FACE AND HANDS FOR A CLOCK

Jerome W. Emdur, Philadelphia, Pa., assignor to Emdur
Metal Products, Inc., Camden, N.J.

Filed Jan. 7, 1970, Ser. No. 20,797

Term of patent 14 years

Int. Cl. D10—06

U.S. Cl. D42—7

Fig. 1

Fig. 2.

Fig. 6.

Fig. 4

Fig. 3

Fig. 7

FIG. 1 is a front elevational view of a combined face and hands for a clock showing my new design;

FIG. 2 is a fragmentary elevational view with the hands omitted for clarity of illustration;

FIG. 3 is a reduced scale rear elevational view;

FIG. 4 is an elevational view from the left of FIG. 3;

FIG. 5 is an elevational view from the right of FIG. 3;

FIG. 6 is a plan view from the top of FIG. 3; and

FIG. 7 is a plan view from the bottom of FIG. 3.

I claim:

The ornamental design for a combined face and hands for a clock, substantially as shown and described.
